Primary Examiner — Austin Murphy(74) *Attorney, Agent, or Firm* — Kevin P. Crosby; GrayRobinson, P.A.(57) **CLAIM**

The ornamental design for modified hole card reader, as shown and described.

DESCRIPTION

FIG. 1. is a front perspective view of the design.

FIG. 2. is a top plan view of the design.

FIG. 3. is a right side elevational view of the design.

FIG. 4. is a front elevational view thereof.

FIG. 5. is a bottom plan view thereof.

FIG. 6. is a rear elevational view thereof.

FIG. 7. is a left side elevational view thereof.

FIG. 8. is a right front perspective view thereof.

FIG. 9. is a left front perspective view thereof; and,

FIG. 10. is a right rear perspective view thereof.

The broken lines shown in the drawings represent portions of the modified hole card reader that form no part of the claimed design.
